UNITED STATES PATENT OFFICE.

MOSES D. BROWN, OF BALTIMORE, MARYLAND

GARMENT-SUPPORTER.

1,183,060.

Specification of Letters Patent.

Patented May 16, 1916.

Application filed August 21, 1912. Serial No. 716,256.

To all whom it may concern:

Be it known that I, Moses D. Brown, a citizen of the United States, residing at Baltimore, State of Maryland, have invented 5 new and useful Improvements in Garment-Supporters, of which the following is a specification.

The invention relates to apparel and has 10 for an object to provide a garment sup- porter.

The invention resides in a supporter adapted more particularly for use in supporting hose such as are worn by men and known as socks.

15 The supporter includes an article having a plurality of adjustments and three points of connection with the sock in a manner which will prevent the sock from sagging in the back and which will also serve to relieve 20 the tension or stress on the calf of the leg.

In the further disclosure of the invention reference is to be had to the accompanying drawings constituting a part of this specification, in which similar characters of reference denote corresponding parts in all the 25 views, and in which:

Figure 1 is a perspective view of the device showing the same in applied position; Fig. 2 is a plan view of the device showing 30 the same in open or unfolded position; and Fig. 3 is a vertical longitudinal sectional view taken on the line 3—3 in Fig. 2.

Referring more particularly to the views, use is made of a plurality of similar sup- 35 porting pads 10, 11 and 12, the said pads being each preferably formed of cloth-like material having a triangular shape and provided with perforations 13 for the purpose of ventilation.

40 An elastic strap 14 has connection with one of the ends of the supporting pad 10 and is passed through a suitable buckle 15, the said strap being then passed through a stirrup 16 secured to an end of the support- 45 ing pad 11, the free end of the strap being then engaged with a medial portion of the buckle 15, thus connecting the pads 10 and 11, the buckle 15 being preferably of a friction type so that by sliding the buckle on 50 the strap 14, the distance between the supporting pads 10 and 11 can be increased or decreased to the convenience of the wearer as will be readily understood by referring to the views. An elastic strap 17 similar to

the elastic strap 14 is connected to the sup- 55 porting pad 12 and is passed through a buckle 18, similar to the buckle 15, after which the said strap 17 is passed through a stirrup 19, similar to the stirrup 16, and secured to another end of the supporting pad 11, the free end of the said elastic strap 17 being then engaged with a medial portion of the buckle 18, thus providing an adjustment between the supporting pads 11 and 12 of a construction similar to the adjust- 60 ment between the supporting pads 10 and 11. It will now be seen that for the supporting pads 10, 11 and 12 a plurality of 65 adjustments are provided and in order to secure the device on the limb of the wearer 70 an attaching member 20 is secured to the supporting pad 12 and adapted for removable connection with a securing member 21 secured to the supporting pad 10, the mentioned attaching member 20 and securing 75 member 21 constituting a suitable clasp 22 of any well known type. Each of the supporting pads 10, 11 and 12 have mounted thereon a gripping member 23 adapted for gripping engagement with the upper edge 80 of a sock 24 as shown in Fig. 1, the mentioned gripping members being of any preferred type and the said supporting pads 10, 11 and 12 being arranged in such a manner that the sock will be gripped by the 85 gripping members 23 at the back and at two places in the front, thus preventing any sagging of the sock on the limb of the wearer, it being further seen that by providing 90 the adjusting means mentioned heretofore and comprising the elastic straps 14 and 17 having the buckles 15 and 18 thereon, the distance between the supporting pads 10, 11 and 12 can be conveniently varied 95 in order to secure a proper adjustment of the article upon the limb of the wearer.

Although I am aware that garment sup- 100 porters for use in supporting socks have been used heretofore, I find that the mentioned supporters do not properly secure the sock and prevent the same from sagging in view of the fact that the supporters simply grip the sock in one or two places and usually at the front of the sock, thus causing the rear of the sock to sag. In my device, 105 however, I provide three points of connection with the sock and it should be noted that in applying the device to the leg to sup-

port the sock at three distinct places, the intermediate supporting pad 11 engages the back of the leg, thus forming a cushion which, together with the supporting function of the intermediate pad, provides a device which takes the usual strain off the rear portion of the leg and also prevents the garter from cutting into the leg as is the case with the garters now generally in use. The 10 garters now generally used which have only one or two points of connection with the hose not only permit the hose to sag at the rear but also cut into the leg in view of the fact that the entire pull on the garter is at 15 the single point of connection of the garter with the hose. It will thus be readily understood that when three points of connection with the hose are provided, the pull on the garter is equally distributed and therefore 20 the garter will lie flat against the leg and will not cut into the same, while at the same time any sagging of the hose at the rear is prevented.

Having thus described my invention, I claim:

A supporter consisting of substantially three triangularly shaped members, a link secured upon the opposite ends of one of said members, adjustable elastic strips slidably disposed in said links at one end, and secured at their opposite ends upon the other two of said triangularly shaped members whereby to form a unitary band, securing elements loosely mounted upon the tab portions of said members, and pivoted interengagable fasteners secured upon the outer ends of the outer of said triangular shaped portions whereby to secure the ends of said supporter together. 25 30 35

In testimony whereof I affix my signature 40 in presence of two witnesses.

MOSES D. BROWN.
